REFRIGERATION

Curtis C. Coons and Clarence G. Puchy, North Canton, Ohio, assignors to The Hoover Company, North Canton, Ohio

Application February 5, 1940, Serial No. 317,384

12 Claims. (CL. 62—119.5)

This invention relates to the art of refrigeration and more particularly to a novel absorption refrigerating system involving unique control and regulating features.

This invention particularly relates to three-fluid absorption refrigerating systems of the type in which a fluid circulating motor is hermetically sealed within the system in order to circulate the fluids therein contained.

In previous constructions considerable difficulty has been experienced due to the fact that ordinary control mechanisms simultaneously energized the circulator and the heater for the boiler, thus initiating circulation of the inert gas and absorbing solution before the boiler heater has had an opportunity to heat the boiler and its contents to the point where refrigerant vapor is evolved therefrom. This represents a direct loss of electrical energy and a direct heat loss by reason of the fact that absorbing solution is circulated through the boiler, cooled in the absorber and returned to the boiler without having refrigerant vapor evolved therefrom. Moreover, the inert gas circulates through the absorber in contact with the liquid previously heated to some extent in the boiler, is heated and after being heated in such fashion the inert gas is propelled through the evaporator which is in the refrigerated space, thus further warming that space and effectively increasing the ultimate refrigerating load upon the apparatus.

In domestic refrigerating systems of the type herein under consideration the fluids may be circulated by means of a very small electrical motor which is hermetically sealed within the system. Such motors are efficient and operate satisfactorily on an electrical input of a very few watts. However, they do not develop a high running or starting torque. The running torque is sufficient for all practical purposes but it is desirable to provide some means to increase the starting torque of such small electrical motors.

Accordingly, it is a principal object of the present invention to provide a three-fluid absorption refrigerating system of the type utilizing a heater for the boiler and a power driven fluid circulator with a control mechanism which will permit the boiler to be heated to the point of evolving refrigerant vapor prior to energization of the fluid circulator and which will permit the fluid circulator to operate for a short period of time on a special circuit which will provide high starting torque and which will generate a relatively high quantity of heat in order to soften the lubricant around the motor bearings and also

to bring the motor as a whole up to its efficient operating temperature.

It is another object of the present invention to provide an absorption refrigerating system of the type above referred to in which the circulator is energized when the temperature of a portion of the apparatus definitely indicates that vapor is being produced in the boiler by the boiler heater. Furthermore, it is an object of the present invention to provide a means whereby the circulator once energized operates upon a starting cycle which produces high torque and high heat in the windings in order to insure starting of the motor and to bring the same up to operating temperature.

It is another object of the invention to provide means arranged to change the circulating motor from a starting circuit to a running circuit in response to a condition of the apparatus indicating that the condition of the system is such that the motor will operate dependably on a running circuit.

Other objects and advantages of the invention will become apparent as the description proceeds when taken in connection with the accompanying drawing in which:

Figure 1 is a diagrammatic representation of an absorption refrigerating system embodying the present invention, and

Figure 2 is a partial diagrammatic representation of a modified form of the invention.

Referring now to the drawing in detail and first to Figure 1 thereof, there is illustrated a three-fluid absorption refrigerating system comprising a boiler B, an analyzer D, an air-cooled rectifier R, a tubular air-cooled condenser C, an evaporator E, a gas heat exchanger G, a tubular inclined air-cooled absorber A, a liquid heat exchanger L, a solution reservoir S, and a circulating fan F which is driven by an electrical motor M. These elements are suitably connected by various conduits to form a plurality of gas and liquid circuits constituting a complete refrigerating system to which reference will be made in more detail hereinafter.

The above described refrigerating system will be charged with a suitable absorbent, such as water, a suitable refrigerant, such as ammonia, and an inert pressure equalizing medium preferably a dense inert gas like nitrogen.

The boiler B is arranged to be heated by a gas burner H which will be described in more detail hereinafter. The application of heat to the boiler B generates refrigerant vapor from the solution therein contained. The vapors so gen-

erated pass upwardly through the analyzer D in counterflow to the strong solution flowing downwardly therethrough. After traversing the analyzer D the vapor is conveyed from the upper portion thereof to the upper portion of condenser C by means of a conduit 11 which includes the rectifier R.

The lean solution formed in the boiler by the generation of refrigerant vapor therefrom is conveyed from the boiler to the solution reservoir S by way of the conduit 12, the liquid heat exchanger L, and a finned looped conduit 13 which also serves as a solution precooler.

The solution reservoir S is vented by means of a conduit 14 which connects to the suction conduit 15 of the circulating fan F. The conduit 15 extends between the suction side of the fan F and the upper portion of the absorber A.

The lean solution is conveyed from the reservoir S to the conduit 15 adjacent its point of connection with the absorber A by means of a gas lift pumping conduit 16. Pumping gas is supplied to the conduit 16 by means of a conduit 17 which is connected between the discharge conduit 18 of the circulating fan F and the gas lift pump 16 below the liquid level normally prevailing therein and in the solution reservoir S.

The lean solution flows downwardly through the absorber A in counterflow relationship to a rich mixture of inert gas and refrigerant vapor which is supplied to the bottom portion of the absorber from the evaporator in a manner to be described hereinafter.

In its traverse through the absorber the lean solution absorbs refrigerant vapor from the gas mixture flowing therethrough and the resulting heat of absorption is rejected by the cooling fins to cooling air flowing over the exterior walls of the absorber vessel.

The strong solution thus formed in the absorber is conveyed therefrom to the upper portion of the analyzer D by way of the conduit 19, the liquid heat exchanger L, and a conduit 20, thus completing the absorption solution circuit.

Lean inert gas is formed in the absorber A by the absorption of refrigerant vapor and is then conveyed from the upper portion of the absorber to the suction side of the circulating fan F by means of the conduit 15. The inert gas is placed under pressure by the fan F and is then conveyed 50 therefrom to the lower portion of the evaporator E by way of the conduit 18, the outer path of the gas heat exchanger G and an evaporator gas supply conduit 22.

The refrigerant vapor which is supplied to the condenser C is liquefied therein by heat exchange relationship with atmospheric air and is then conveyed therefrom to the bottom portion of the evaporator E by way of the conduit 23 and a conduit 24 which includes a downwardly extending U-shaped looped portion which is designed to carry a liquid seal and a pressure balancing column of the liquid refrigerant. The conduits 23 and 24 are vented by means of a conduit 25 to the rich gas side of the gas heat exchanger G. As a result of this construction the pressure prevailing in the condenser and the condenser side of the conduit 24 is that prevailing on the discharge side of the evaporator whereas the pressure prevailing on the discharge side of the conduit 26 is that prevailing at the inlet to the evaporator. This pressure difference is compensated by a pressure balancing liquid column which is supported in the condenser side of the conduit 24.

The evaporator E may be of any desired type of construction. However, as diagrammatically illustrated herein, it is of the type in which the high velocity gas stream flowing through the evaporator serves to sweep or drag liquid refrigerant upwardly therethrough as it is evaporating to produce refrigeration. A preferred construction of this type evaporator is disclosed and claimed in the co-pending application of Curtis 5 C. Coons and William H. Kitto, Serial No. 220,189, filed July 20, 1938.

An anti-blocking and overflow drain 27 is connected between the upper portion of the bottom conduit in the evaporator E and the strong solution return conduit 19.

The liquid refrigerant supplied to the bottom portion of the evaporator E meets a high velocity gas stream flowing upwardly therethrough with the result that the liquid refrigerant is propelled 20 upwardly through the evaporator as it is evaporating into the gas stream to produce useful refrigeration.

The top portion of the evaporator is provided with a large diameter finned box-cooling conduit 25 28 into which both the liquid and gas discharge. The gas flows at a slow rate through this conduit, hence the same is inclined rearwardly in order to permit liquid to flow by gravity. The resulting rich gas and unevaporated material in the 30 evaporator is conveyed from the conduit 28 into the rich gas side of the gas heat exchanger G by means of a conduit 29. After traversing the rich gas side of the gas heat exchanger the rich gas and unevaporated material is drained therefrom 35 into the bottom portion of the absorber A by means of the conduit 30. Thus, the conduit 30 serves as a rich gas return conduit and as an evaporator drain. The rich gas then flows upwardly through the absorber A in counterflow 40 relationship with the lean solution flowing downwardly therethrough in the manner heretofore described.

It will be noted that with the construction thus provided evaporator drainage is conveyed to the conduit 19 in a manner such that it cannot reach the circulating fan and the fan is so connected to the absorber that lean solution cannot be conveyed thereto from the lean solution supply lines.

The circulating motor fan assembly comprises a conventional gas fan which is sealed within the housing F and arranged to receive gas from the suction conduit 15 and to discharge the same into the discharge conduit 18 in a conventional manner. This fan is driven by an electrical motor of the induction type which includes a rotating part hermetically sealed within the system within a motor shell 32 and which is driven by a suitable field construction 33 which is mounted upon the exterior wall of the shell 32.

The heater H for the boiler B is supplied with fuel through a suitable gas supply conduit 35 which includes the solenoid valve V and a suitable thermostatic safety cut-off device 36 which will completely shut off the supply of flame to the heater H upon complete flame failure thereat. A small by-pass 37 is provided around the solenoid valve V in order to provide a small pilot or ignition flame upon the burner H when the valve V is in closed position.

Electrical energy for the valve V and motor M is supplied from a suitable pair of electrical conductors 40 and 41.

The conductor 40 connects directly to a thermostatic control mechanism 42 of a conventional

type which consists essentially of a thermostatic switch arranged to respond to the temperature at or adjacent the evaporator E by means of a capillary conduit 43 and thermostatic bulb 44.

The stator winding 45 of the electrical motor M is indicated diagrammatically thereabove in order to facilitate understanding of the invention. One side of the winding 45 is connected by means of an electrical conductor 46 to the solenoid valve V and the conductor 46 is connected by means of a conductor 47 to the thermostatic switching mechanism 42.

The conductor 41 is connected to a conductor 48 which is connected between the solenoid valve V and the movable contact 49 of a thermostatic snap-acting toggle switch 50. The stationary contact 51 of the switch 50 is connected by means of a conductor 52 to the movable contact 53 of a second snap-acting toggle switch mechanism 54. The switch 54 includes a pair of spaced-apart stationary contacts 55 and 56. The contact 55 is connected to the other end of the winding 45 by means of an electrical conductor 57 and the contact 58 is connected to the central portion of the winding 45 by means of an electrical conductor 59, thus completing the electrical control circuits for the apparatus.

The snap acting toggle switch 50 is arranged to be actuated by means of a thermostat 60 which is positioned to be influenced by the thermal condition of the vapor conduit 11 just beyond the finned rectifier portion thereof.

The thermostatic switch mechanism 54 is arranged to be actuated by a thermostat 61 which is also positioned to be influenced by the thermal condition of the conduit 11 but at a point between the condenser and the thermostatic element 60. The thermostatic switch mechanism may be enclosed in suitable housing, if desired, as indicated in dotted lines.

The operation of the apparatus except insofar as the same has already been described in describing the refrigerating mechanism per se is as follows: When the apparatus is originally installed all portions thereof will be substantially at atmospheric temperature wherefore the thermostatic switching mechanism 42 will have closed the circuit between the conductors 40 and 41, the switch 50 will be in open circuit position by reason of the thermostat 60 assuming the dotted line position indicated in Figure 1 and the switch contact 53 will be in contact with the stationary contact 55 by reason of the thermostat 61 being in the dotted line position indicated in Figure 1. Therefore, as soon as the apparatus is connected to suitable sources of electrical energy, the valve V will open due to the energization of the conductors 46 and 48, and a full flame will be carried upon the burner which will serve to heat the boiler B and its contents but the motor M will not be operated because of the open-circuit position existing at the switching mechanism 50. Heat will continue to be applied to the boiler B from the burner H for a sufficient period of time to bring the same to the boiling point and to evolve refrigerant vapor without meeting the losses attendant upon circulation of the inert gas and solution at this time. Refrigerant vapor will then begin to flow through the conduit 11 to the condenser C and will very quickly heat the conduit 11 sufficiently to actuate the thermostat 60 to the solid line position indicated in Figure 1 which will close the circuit between the contacts 49 and 51, thereby energizing the circulator motor through the following circuits: 40, 42, 47, 48, 75

lower half of 45 as viewed in Figure 1, 58, 56, 53, 52, 51, 49, 48, 41. This circuit will energize only a portion of the motor windings wherefore the same will take a very high current which will provide the motor with a starting torque, two to three times normal, and will also generate a rather large quantity of heat. Such a motor winding arrangement is not efficient but it is not objectionable as a starting device. The high starting torque provided by the circuit just described will insure that the motor will start immediately the thermostat 60 flexes to the closed circuit position and will also produce a large quantity of heat which will serve quickly to heat the motor to its operating temperature and will also quickly soften the lubricant in the motor bearings in the event that the same is stiff or will not flow readily.

The above described operation of the apparatus will continue for a short period of time until the higher portion of the conduit 11 with which the thermostat 61 is in heat exchange relation has been heated by the hot vapor flowing therethrough. When this occurs the thermostatic element 61 shifts from the dotted line position shown in Figure 1 to the solid line position, thus snapping the contact 53 from its position against the contact 56 to a position against the contact 55. The entire motor winding is now energized as the current previously supplied to the switch arm 53 now flows through 53, 55, 57 and throughout the motor winding 45. This is the running condition of the motor in which the current consumed by the same is much lower than that consumed on starting and in which the motor operates at its highest efficiency. Under these conditions the torque produced by the motor is lower than that produced in the starting circuit but it is ample for operating conditions.

The above described circuits will be maintained until such time as the temperature at or adjacent the evaporator has reached the value for which the thermostatic control mechanism 42 is set at which point the mechanism 42 will open the electrical circuit between the conductors 40 and 41.

After de-energization of the valve and motor by the thermostatic control mechanism 42 the conduit 11 will quickly cool and the thermostatic elements 60 and 61 will move to the dotted line position indicated in Figure 1, thereby opening-circuiting the switch 50 and shifting the movable contact arm 53 into engagement with the stationary contact 56 to condition the apparatus for the next cycle of operation.

In Figure 2 there is illustrated a modified form of the invention. The invention of Figure 2 is designed and intended to be utilized with a refrigerating system identical with that disclosed in Figure 1, hence only the control mechanism and its immediately associated portions of the apparatus have been illustrated in this figure. Certain portions of the apparatus illustrated in Figure 2 are identical with apparatus previously illustrated and described in connection with Figure 1 and they are therefore given the same reference characters primed.

As may readily be seen from an inspection of Figure 2, the heating arrangement for the boiler is identical with that described in connection with Figure 1 as is the motor fan arrangement. Only the control mechanism differs.

In the form of the invention in Figure 2 electrical energy is supplied to the apparatus

through a pair of electrical conductors 60 and 61. Electrical conductor 60 connects directly to the thermostatic control switch 42' which is then connected by means of a conductor 63 to a conductor 62 which connects the solenoid valve V' and one end of the motor field winding 45'. The conductor 61 connects directly to the valve V' and is connected by means of a conductor 64 to the movable contact 65 of a snap acting toggle switch 66 arranged to be actuated by thermostatic bellows 67. The bellows 67 is provided with a capillary tube and bulb assembly 68 which is positioned in heat exchange relationship with the vapor line 11' above the rectifier R'.

The active contact 69 of the switch assembly 66 is connected to the movable contact 70 of a second snap acting thermostatic switch 71 by means of an electrical conductor 72. The left hand contact 73 of the switch 71 is connected by means of an electrical conductor 74 to the mid point of the motor field winding 45' and the contact 75 of the switch 71 is connected to the opposite end of the motor field winding 45' by means of an electrical conductor 76, thus completing the electrical control circuit of the apparatus. The switch 71 is actuated by a thermostatic bellows 78 which is arranged to be responsive to the temperature of the motor shell 32' by means of a capillary tube 79 which connects the bellows to a bulb 80 positioned against the bottom wall of the shell 32'.

This form of the invention operates in substantially the same manner as that described in connection with Figures 1 and 2 except that the circulating motor in this instance is shifted from the starting cycle to the running cycle in response to the temperature of the motor shell 32' rather than in response to the temperature condition of a portion of the vapor line connecting the analyzer and condenser and remote from the analyzer.

The advantage of this form of the invention is that in installations using a rather stiff lubricant for the motor it is desirable to maintain the motor on the operating and starting cycle until the motor assembly has warmed up sufficiently to operate efficiently and to soften the lubricant to the point where it does not impose an appreciable drag on the rotating part of the motor before shifting the same to the running winding which operates with a low torque but with a high electrical efficiency. This form of the invention is also desirable for installations in cool climates because it prevents operation of the motor on its running circuit until it has reached its normal operating temperature.

Therefore, in accordance with this form of the invention a demand for refrigeration will cause energization of the solenoid valve V' through the circuits 60, 42', 63, 62, V' 61.

After the boiler has been brought into operating condition and has heated the conduit 11 the switch 66 will close the circuit between the conductors 64 and 72 by which the motor starting cycle will be completed through the following circuit: 60, 42', 63, 62, lower half of the winding 45', conductors 74, 73, 70, 72, 69, 68, 64, 61.

After the motor has warmed up appreciably the bellows 78 through its capillary tube and bulb assembly 79 and 80 responds to an increase in temperature on the part of the motor shell 32' and expands thus actuating the snap-acting switch mechanism 71 to break the circuit at the point 73 and to close the circuit at the point 75, thus ener-

75 gizing the entire running winding and placing the apparatus in normal running condition.

Both forms of the invention herein disclosed provide a highly efficient and desirable control arrangement in that energization of the fluid circulator is not initiated until the boiler is brought into operating condition, thereby obviating heat losses due to circulation of the inert gas and absorption solution as well as the electrical loss entailed by useless operation of the motor fan unit.

Moreover, a high torque starting circuit is provided to bring the motor quickly into efficient operating condition after which the motor is shifted to its low torque high efficiency running circuit in response either to an increase in the temperature on the part of a portion of the vapor line remote from the boiler or in response to a change in the temperature condition of the motor shell construction.

While we have shown but one embodiment of our invention, it is to be understood that this embodiment is to be taken as illustrative only and not in a limiting sense. We do not wish to be limited to the particular structure shown and described but to include all equivalent variations thereof except as limited by the claims.

We claim:

1. Absorption refrigerating apparatus including a generator, a heater for said generator, a fluid circulator, power operated means for driving said circulator, refrigeration demand responsive means for controlling said heater, means responsive to a change in the condition of a portion of said apparatus reflecting a change in the operating condition of said heater for energizing starting connections for said power operating means, and means for subsequently deenergizing said starting connections and for energizing running connections for said power operated means.

2. Absorption refrigerating apparatus including a generator, a heater for said generator, a fluid circulator, power operated means for driving said circulator, refrigeration demand responsive means for controlling said heater, means responsive to a change in the condition of a first portion of said apparatus reflecting a change in the operating condition of said heater for energizing starting connections for said power operated means, and means for subsequently deenergizing said starting connections and for energizing running connections for said power operated means in response to a change in the condition of a second portion of the apparatus.

3. Absorption refrigerating apparatus including a generator, a condenser, an evaporator, an absorber, and a fluid circulator connected in circuit, a motor for driving said circulator, said circuit including refrigerant vapor conducting means connecting said generator to said condenser, a heater for said generator, means for controlling the operation of said heater in response to refrigeration demand, starting connections for said motor, means responsive to the temperature of said vapor conducting means for energizing said starting connections, running connections for said motor, and means for de-energizing said starting connections and for energizing said running connections.

4. Absorption refrigerating apparatus including a generator, a condenser, an evaporator, an absorber, and a fluid circulator connected in circuit, a motor for driving said circulator, said circuit including refrigerant vapor conducting means connecting said generator to said con-

denser, a heater for said generator, means for controlling the operation of said heater in response to refrigeration demand, starting connections for said motor, means responsive to the temperature of said motor conducting means for energizing said starting connections, running connections for said motor, and means responsive to the temperature of a portion of said vapor conducting means further removed from said generator than the portion thereof to which said starting connections energizing means is responsive for de-energizing said starting connections and for energizing said running connections.

5. Absorption refrigerating apparatus including a generator, a condenser, an evaporator, an absorber, and a fluid circulator connected in circuit, a motor for driving said circulator, said circuit including refrigerant vapor conducting means connecting said generator to said condenser, a heater for said generator, means for controlling the operation of said heater in response to refrigeration demand, starting connections for said motor, means responsive to the temperature of said vapor conducting means for energizing said starting connections, running connections for said motor, and means responsive to the temperature of said motor for de-energizing said starting connections and for energizing said running connections after said motor has been brought into operating condition.

6. Absorption refrigerating apparatus including a generator, a conduit for conducting refrigerant vapor away from said generator, a fluid circulator, a motor for driving said fluid circulator having a field winding including high torque and high heating starting connections and running connections, a heater for said generator, means for rendering said heater operative and inoperative in response to refrigeration demands, means for energizing said starting connections when refrigerant vapor is discharged from said generator, and means for subsequently de-energizing said starting connections and for energizing said running connections.

7. Absorption refrigerating apparatus including a generator, a conduit for conducting refrigerant vapor away from said generator, a fluid circulator, a motor for driving said fluid circulator having a field winding including high torque and high heating starting connections and running connections, a heater for said generator, means for rendering said heater operative and inoperative in response to refrigeration demands, means for energizing said starting connections when refrigerant vapor is discharged from said generator, and means responsive to the thermal condition of a portion of said vapor conduit removed from said generator for de-energizing said starting connections and for energizing said running connections.

8. Absorption refrigerating apparatus including a generator, a conduit for conducting refrigerant vapor away from said generator, a fluid circulator, a motor for driving said fluid circulator having a field winding including high torque and high heating starting connections and running connections, a heater for said generator, means for rendering said heater operative and inoperative in response to refrigeration demands, means for energizing said starting connections when refrigerant vapor is discharged from said generator, and means for de-energizing said starting connections and for energizing said running connections when said motor has reached its operating temperature.

9. An absorption refrigerating system comprising an inert gas circuit including an evaporator and an absorber, a solution circuit including a boiler and said absorber, means for liquefying refrigerant vapor produced in said boiler and for supplying the liquid to said evaporator, means for circulating inert gas and absorption solution through said inert gas and absorption solution circuits respectively, a motor for driving said last mentioned means having starting and running connections, a heating means for said boiler, control means for energizing and deenergizing said heater in response to refrigeration demand, means for energizing said starting connections after said boiler has begun to discharge refrigerant vapor, and means for subsequently energizing said running connections.

10. An absorption refrigerating system comprising an inert gas circuit including an evaporator and an absorber, a solution circuit including a boiler and said absorber, means for liquefying refrigerant vapor produced in said boiler and for supplying the liquid to said evaporator, means for circulating inert gas and absorption solution through said inert gas and absorption solution circuits respectively, a motor for driving said last mentioned means, a heating means for said boiler, said motor including a field winding having a connection intermediate its ends whereby only a portion thereof may be energized to provide for high starting torque and rapid initial motor heating, control means for rendering said heater operative and inoperative in accordance with refrigeration demand, means for connecting said intermediate connection and one end of said winding to a source of electrical energy after said boiler has been placed in operation by said heater, and means for subsequently disconnecting said intermediate connection and for connecting the other end of said winding to said source of electrical energy.

11. Absorption refrigerating apparatus including a generator, a condenser, an evaporator, an absorber, and a fluid circulator connected in circuit, a motor for driving said fluid circulator, said circuit including refrigerant vapor conducting means connecting said generator to said condenser, a heater for said generator, means for controlling the operation of said heater in response to refrigeration demand, starting connections for said motor, means for energizing said starting connections in time delayed relationship with the operation of said heater, running connections for said motor, and means responsive to the temperature of said vapor conducting means for de-energizing said starting connections and for energizing said running connections.

12. Absorption refrigerating apparatus including a generator, a heater for said generator, a fluid circulator, power operated means for driving said circulator, refrigeration demand responsive means for controlling said heater, means responsive to a change in the condition of a portion of said apparatus reflecting a change in the operating condition of said heater for energizing starting connections for said power operated means in timed delayed relationship with said change in the operating condition of said heater, and means for subsequently de-energizing said starting connections and for energizing running connections for said power operated means.
